3,000,951
NITRAMINES

Milton B. Frankel, Pasadena, and Karl Klager, Monrovia, Calif., assignors to Aerojet-General Corporation, Azusa, Calif., a corporation of Ohio
No Drawing. Filed Mar. 7, 1957, Ser. No. 644,692
10 Claims. (Cl. 260—583)

This invention relates to new compositions of matter and a method for their preparation. In particular, this invention relates to nitramines having the general formula:

wherein R is an alkyl or nitro radical and A is an alkylene radical.

This application is a continuation-in-part of our pending United States patent application Serial No. 421,987, filed April 8, 1954, now abandoned.

The nitro compounds of this invention are useful as high explosives and can be used in any conventional explosive missile, projectile, rocket, or the like, as the main explosive charge. An example of such a missile is disclosed in United States Patent No. 2,470,162, issued May 17, 1949. One way of using the high explosives of this invention in a device such as that disclosed in United States Patent No. 2,470,162, is to pack the crystalline explosive in powder form into the warhead of the missile. Alternatively, the crystals can be first pelletized and then packed. A charge thus prepared is sufficiently insensitive to withstand the shock entailed in the ejection of a shell from a gun barrel or from a rocket launching tube under the pressure developed from ignition of a propellant charge, and can be caused to explode on operation of an impact- or time fuse-mechanism firing a detonating explosive such as lead azide or mercury fulminate.

The compounds of this invention are readily prepared by reacting the corresponding amine with nitric acid, as illustrated by the general reaction scheme set forth below:

wherein R and A are as defined above.

The amines used as starting materials in this invention are readily obtained by the condensation of primary amines with 2,2-dinitro-1,3-propanediol, as disclosed in our copending application Serial No. 419,616, filed March 29, 1954, now abandoned.

To more clearly illustrate this invention, the following examples are presented. It should be understood, however, that these examples are presented merely as a means of illustration and are not intended to limit the scope of the invention in any way.

EXAMPLE I

Preparation of 1,1,1,4,6,6,8,11,11,11-decanitro-4,8-diaza undecane

A solution of 40 ml. of 100% nitric acid and 40 ml. of acetic anhydride was cooled to a temperature of 5° C. and 4.1 gm. of 1,1,1,6,6,11,11,11-octanitro-4,8-diaza undecane was added. On warming to room temperature the solid dissolved. The solution was poured onto ice

2

causing a cream-colored gummy solid to precipitate. The product was washed with water and dried. Recrystallization from concentrated nitric acid gave white needles, M.P. 135–137° C., exhibiting an impact stability of 10–15 cm./2 kg. The elemental analysis of the product is as follows:

Calculated for $\text{C}_9\text{H}_{12}\text{N}_{12}\text{O}_{20}$: Percent C, 17.77; percent H, 1.99; percent N, 27.64. Found: Percent C, 18.29; percent H, 2.02; percent N, 27.40.

10 The product had a calculated heat of combustion of 20.44 cal./gm. and was found to be 1984 cal./gm. The explosive power of this compound is as follows:

Lead block value, 177; T.N.T.=100
Ballistic mortar value, 155; T.N.T.=100

EXAMPLE II

Preparation of 2,2,5,7,7,9,12,12-octanitro-5,9-aza tridecane

20 2,2,5,7,7,9,12,12-octanitro-5,9-aza-tridecane was prepared by treating 2,2,7,7,12,12-hexanitro-5,9-aza-tridecane with nitric acid in the manner described in Example I. The product, recrystallized from ethylene dichloride, had a M.P. of 137–139° C. The elemental analysis of the product is as follows:

Calculated for $\text{C}_{11}\text{H}_{18}\text{N}_{10}\text{O}_{18}$: Percent C, 24.18; percent H, 3.32; percent N, 25.64. Found: Percent C, 24.76; percent H, 3.44; percent N, 25.52.

This compound had a calculated heat of combustion of 2879 cal./gm. and was found to be 2897 cal./gm. The explosive power of this compound is as follows:

Lead block value, 128; T.N.T.=100
Ballistic mortar value, 140; T.N.T.=100

35 We have also found that amines such as 2,2,8,8,14,14-hexanitro-6,10-diaza pentadecane, 4,4,9,9,14,14-hexanitro-7,11-diaza heptadecane, 2,2,6,6,10,10-hexanitro-4,8-diaza undecane, 1,1,1,5,5,9,9,9-octanitro-3,7-diaza nonane and 2,16-dimethyl-3,3,9,9,15,15-hexanitro-7,11-diaza heptadecane readily undergo nitration with nitric acid to form their corresponding nitramines, namely, 2,2,6,8,8,10,14,14-octanitro-6,10-diaza pentadecane, 4,4,7,9,9,11,14,14-octanitro-7,11-diaza heptadecane, 2,2,4,6,6,8,10,10-octanitro-4,8-diaza undecane, 1,1,1,3,5,5,7,9,9,9-decanitro-3,7-diaza nonane, and 2,16-dimethyl-3,3,7,9,9,11,15,15-octanitro-7,11-diaza heptadecane.

40 It is apparent that any nitramine of the disclosed series can be prepared by merely selecting an appropriate amine and reacting it with nitric acid, in accordance with the teachings of this invention.

We claim:

1. As compositions of matter, nitramines having the formula:

55 wherein R is a radical selected from the group consisting of nitro and lower alkyl radicals and A is a lower alkylene radical.

2. As compositions of matter, nitramines having the formula:

60 wherein A is a lower alkylene radical.

3. As compositions of matter, nitramines having the formula:

65 70

wherein R is a lower alkyl radical and A is a lower alkylene radical.

4. As a composition of matter, 1,1,1,4,6,6,8,11,11,11-decanitro-4,8-diaza undecane having the structural formula:

5. As a composition of matter, 2,2,5,7,7,9,12,12-octanitro-5,9-diaza tridecane having the structural formula:

6. The method of preparing nitramines having the formula:

which comprises reacting nitric acid with an amine having the formula:

wherein R is a radical selected from a group consisting of lower alkyl and nitro radicals and A is a lower alkylene radical.

7. The method of preparing nitramines having the formula:

5 which comprises reacting nitric acid with an amine having the formula:

wherein A is a lower alkylene radical.

6. The method of preparing nitramines having the formula:

which comprises reacting nitric acid with an amine having the formula:

25 wherein R is a lower alkyl radical and A is a lower alkylene radical.

9. The method of preparing 2,2,5,7,7,9,12,12-octanitro-5,9-diaza tridecane which comprises reacting 2,2,7,7,12,30 12-hexanitro-5,9-diaza tridecane with nitric acid.

10. The method of preparing 1,1,1,4,6,6,8,11,11,11-decanitro-4,8-diaza undecane which comprises reacting 1,1,1,6,6,11,11,11-octanitro-4,8-diaza undecane with nitric acid.
